UNITED STATES PATENT OFFICE.

LOUIS F. RUNYAN, OF LEBANON, OHIO.

HAY-RIGGING.

1,213,023.

Specification of Letters Patent. Patented Jan. 16, 1917.

Application filed April 18, 1916. Serial No. 92,029.

To all whom it may concern:

Be it known that I, LOUIS F. RUNYAN, a citizen of the United States, residing at Lebanon, in the county of Warren and State of Ohio, have invented new and useful Improvements in Hay-Riggings, of which the following is a specification.

This invention relates to hay riggings, and it has particular reference to the mounting of the ladders at the front and rear ends of a hay rack.

The invention has for its object to produce simple and improved means for mounting the hay ladders in such a fashion that they may be folded down flat on the rack when not in use, and will on the other hand be sustained securely in position when raised.

A further object of the invention is to produce specially constructed socket members that form bearings for the rock shafts of the hay ladders, said sockets being so constructed as to enable the hay ladder to be readily removed without disassembling the hay rack, and said socket members being equipped with latch means of special construction for securing the hay ladders in position when raised to an upright position.

With these and other ends in view which will readily appear as the nature of the invention is better understood, the same consists in the improved construction and novel arrangement and combination of parts which will be hereinafter fully described and particularly pointed out in the claims.

In the accompanying drawings has been illustrated a simple and preferred form of the invention, it being, however, understood that no limitation is necessarily made to the precise structural details therein exhibited, but that changes, alterations and modifications within the scope of the claims may be resorted to when desired.

In the drawings, Figure 1 is a view in elevation of a hay ladder constructed in accordance with the invention, showing also in section the sills of a hay rack on which it is mounted. Fig. 2 is a similar view showing the end portions of the rock shaft supporting the ladder and related parts in section. Fig. 3 is a perspective view of one of the bearing sockets which is provided with a latch member. Fig. 4 is a perspective detail view of the other bearing socket. Fig. 5 is a side elevation of the bearing socket

having the latch member, showing the latch member in raised position.

Corresponding parts in the several figures are denoted by like characters of reference.

15 designates the sills of a hay rack, and 16 a cross bar connecting the same. The ladders at the front and rear ends of the rack are of similar construction, and only one has been shown, said ladder being designated by L.

65 Each ladder is composed of side members 18 which are connected together and spaced apart at suitable intervals by rungs 19, the lower ends of the side members being firmly connected with rock shafts 20, said rock 70 shafts being usually made of wood and of square or rectangular cross section throughout the greater portion of the length thereof, each shaft being provided with terminal trunnions 21. The trunnions at the ends of 75 each rock shaft are supported in sockets 22, 23 which are securely mounted on the inner faces of the sills. The sockets 22 are of circular shape, each being provided with flanges 24 for the passage of fastening members, such as bolts 25, whereby the said sockets 22 are secured on one sill. The sockets 23 are substantially U-shaped, open at their ends, said sockets being adapted to be secured by means of bolts 26 on the sills 85 opposite to and in alignment with the sockets 22.

80 The wall members of each socket 23 are provided near their upper ends, where the socket is open, with registering apertures 27, 90 and the rearward wall member has an additional aperture 28 which is located below and to one side of the aperture 27.

95 B is a latch member, the same being formed of a rod of steel or other resilient metal, and the same being bent to form an elongated yoke having limbs 29, 30, one of which, 30, is provided with an offset 31. The limb 29 is bent to form a rocking member or shaft 32 which extends through the 100 apertures 27 for rocking movement therein. The other limb, 30, is extended beneath that portion of the rock shaft 32 which extends through the side walls of the socket, said limb 30 being formed with a terminal lug 33 105 which is adapted to engage the aperture 28 when the latch member is in an approximately horizontal position, thus constituting a locking device whereby the latch member will be securely maintained in such position. 110

When the latch member is in this position, the offset 31 of the limb 30 will abut upon one of the side members of the hay ladder whose rock shaft is supported in the sockets, and such ladder will thus be maintained in an upright position without danger or possibility of being accidentally disengaged and permitted to swing downward.

When it is desired to move the hay ladder to an approximately horizontal position, the latch member B is bent until the free end thereof is moved out of the path of the ladder, as indicated in dotted lines in Fig. 3, thus permitting the ladder to be swung about the axis of its rock shaft 20 until it occupies the desired position, after which the latch member B, being released, will automatically assume its initial position. In like manner the latch member B is manipulated when the ladder is to be restored to an upright position.

That portion of the rock shaft or member 32 which extends beyond the walls of the socket is apertured for the passage of a split 25 key or cotter whereby the parts may be maintained in assembled relation. By swinging the latch member to an upright position, removing the cotter and pulling the limb 30 in an outward direction from the 30 socket until the lug 33 is clear of the wall portion of the socket, the latch member may be readily detached or disengaged from the socket member by simply sliding the rock shaft or member 32 from the apertures 35 wherein it is supported. One end of the rock shaft of the hay ladder may then be lifted through the open portion of the socket member 23, and the other end of the rock shaft of the ladder may now be readily disengaged from the socket member 22. The 40 ladder may thus be readily disengaged or detached from the rack when desired for the purpose of repairing the same or for other reasons, and this may be accomplished without disassembling or in any way injuring the hay rack.

The wall portion of the socket 23 is provided near its upper end with a laterally extending lug 34, the same constituting a 50 stop on which the latch member may be supported in an approximately horizontal position, said stop preventing the movement of the free end of the latch member in a downward direction beyond predetermined limits.

It has been stated that the latch member is constructed of a piece of material which is inherently resilient. By extending the rock shaft 32 formed at the end of the limb 29 of the latch member in the path of the 60 limb 30 it will be seen that the said limb 30 will be disposed tangentially, while the limb 29 is disposed radially with respect to the rock shaft, so that the lug 33 at the end of the limb 30 will readily engage the aperture 28 65 which is formed adjacent to one of the aper-

tures 27. When the lug 33 is disengaged from the aperture 28 and the latch member is moved to an approximately vertical position, it is evident that the lug 33 will abut externally on the wall portion of the socket member 23. On the other hand, when the latch is moved to an approximately horizontal position, the lug 33 will automatically spring into engagement with the aperture 28 at the time when the stop member or lug 75 34 is encountered by the limb 29, the parts being suitably arranged and proportioned with this end in view.

Having thus described the invention, what is claimed as new, is:—

1. The combination with a hay rack having side sills, of socket members mounted on the inner opposed faces of said sills, one of said socket members being open at the top, a hay ladder having a rock shaft provided with terminal trunnions engaging the socket members, and a latch member swingingly connected with the socket member which is open at the top, said latch member having a portion extending through the wall portion 85 of the socket near the open end thereof and lying in the path of one of the trunnions of the rock shaft of the hay ladder.

2. The combination with a hay rack having side sills, of socket members mounted on the inner opposed faces of said sills, one of said socket members being open at the top, a hay ladder having a rock shaft provided with terminal trunnions engaging the socket members, and a latch member swingingly connected with the socket member which is open at the top, said latch member having a portion extending through the wall portion 90 of the socket near the open end thereof and lying in the path of one of the trunnions of the rock shaft of the hay ladder, said latch member having an offset adapted to engage the 95 rock shaft of the hay ladder.

3. The combination with a hay rack having side sills, of socket members mounted on the inner opposed faces of said sills, one of said socket members being open at the top, a hay ladder having a rock shaft provided with terminal trunnions engaging the socket 100 members, and a latch member swingingly connected with the socket member which is open at the top, said latch member having a portion extending through the wall portion 105 of the socket near the open end thereof and lying in the path of one of the trunnions of the rock shaft of the hay ladder, said latch member having an offset adapted to engage the 110 hay ladder to sustain the same in a raised position.

4. The combination with a hay rack having side sills, of socket members mounted on the inner opposed faces of said sills, one of said socket members being open at the top, a hay ladder having a rock shaft provided with terminal trunnions engaging the socket 115 members, and a latch member swingingly connected with the socket member which is open at the top, said latch member having a portion extending through the wall portion 120 of the socket near the open end thereof and lying in the path of one of the trunnions of the rock shaft of the hay ladder, said latch member having an offset adapted to engage the 125 hay ladder to sustain the same in a raised position, said latch member being also provided with means whereby it may be locked securely with respect to the socket member.

5. In a device of the class described, a socket member of substantially U-shape 130

- open at the top, the wall portion of said socket being provided with oppositely disposed registering apertures and with an additional aperture adjacent to one of the first 5 mentioned apertures, in combination with a latch member consisting of a resilient yoke, one limb of which is bent to form a rock shaft engaging the registering apertures in the wall portion of the socket, said rock 10 shaft extending also in the path of the other limb; said other limb being provided with a locking lug adapted to engage the aperture adjacent to one of the registering apertures in the wall portion of the socket. 15 5. In a device of the class described, a socket member of substantially U-shape open at the top, the wall portion of said socket being provided with oppositely disposed registering apertures and with an additional
- aperture adjacent to one of the first men- 20 tioned apertures, in combination with a latch member consisting of a resilient yoke, one limb of which is bent to form a rock shaft 25 engaging the registering apertures in the wall portion of the socket, said rock shaft extending also in the path of the other limb; said other limb being provided with a locking lug adapted to engage the aperture adjacent to one of the registering apertures in the wall portion of the socket; the wall por- 30 tion of the socket being equipped with a stop member lying in the path of the latch member, said stop member being so disposed as to intercept the latch member about the time when the locking lug engages the aperture. 35
In testimony whereof I affix my signature.

LOUIS F. RUNYAN.
